CLAIM

The ornamental design for an electronic enclosure cover, as shown.

DESCRIPTION

FIG. 1 is a perspective view of an electronic enclosure cover as viewed looking downwardly from the right side of our design;

FIG. 2 is an end elevational view of the electronic enclosure cover as viewed looking downwardly from the top of FIG. 1;

FIG. 3 is an elevational view of the left side of the electronic enclosure cover shown in FIG. 1;

FIG. 4 is a front elevational view of the electronic enclosure cover as viewed from the right of FIG. 3; and

FIG. 5 is an end elevational view of the electronic enclosure cover as viewed looking upwardly from the bottom of FIG. 4.

FIG. 1

FIG. 5

FIG. 2

FIG. 4

FIG. 3
